MAGNETIC SEPARATOR AND THE PROCESS
OF SEPARATIONRoswell H. Stearns, Milwaukee, Wis., assignor
to Magnetic Manufacturing Company, Milwaukee, Wis.

Application October 5, 1931, Serial No. 566,885

21 Claims. (Cl. 209—218)

This invention relates to magnetic separators and to the process of separation. In magnetic separators as heretofore constructed it has been the usual practice to separate the magnetic particles from the non-magnetic material. With the separators heretofore constructed it has been difficult to produce a separator which would even inefficiently separate magnetic material to a point where the remaining amount of the magnetic material approximated a negligible value. Even where a very great separation was attained, it was found that the loss of the non-magnetic material was excessive and consequently the process was, from a practical point of view, almost prohibitive.

This invention is designed to overcome the defects noted above, and objects of this invention are to provide a novel form of magnetic separator and a process of separation which will reduce the magnetic content to a very low value without an appreciable loss of the non-magnetic material.

In the usual processes followed for the magnetic separation it has been the practice to remove the magnetic material from the non-magnetic material and it has been found with these processes that a considerable amount of the non-magnetic material was removed with the magnetic material, so that if a high degree of separation was attained, a great loss resulted in the non-magnetic material.

Further, it has been found that difficulty was experienced in the separation, as material ground to a finely divided state, tends to agglomerate, causing irregular feeding, and when distributed to carrier means for separation readily adheres to the same, seriously interfering with the separation of the particles. The loss, under these conditions, of the non-magnetic material was very high and the separation very difficult.

Further objects of this invention are to provide a magnetic separator and a process of separation in which the non-magnetic material is separated from the magnetic material thereby reversing the usual steps in the separation as heretofore commonly employed, and to provide a separator which although capable of handling different forms of material is nevertheless eminently suited to the separation of very finely powdered, non-magnetic material from similarly finely powdered magnetic material, or, in fact, from magnetic material of any form.

Further objects are to provide a magnetic separator in which the mixture of the magnetic and

non-magnetic material is passed through a screen formed of magnetic material, such, for example, as soft iron, and is held in a very strong magnetic field so that the finely powdered, non-magnetic material will pass through the screen, whereas the magnetic material will actually contact with and adhere to the screen, the benefit being taken of the fact that where magnetic material contacts with the magnetized screen, that a very secure holding of the magnetic material is secured, as distinguished from the lifting or removal of the magnetic material from the non-magnetic material.

Further objects are to provide a novel form of separator in which highly efficient means are provided for insuring the passage of the non-magnetic material directly through the screen and for the subsequent removal of the adhering magnetic material from the screen.

Further objects are to provide a magnetic separator which has a high capacity, which will reduce the iron content or magnetic content to a very low value far below that customarily obtained in the usual practice, and to provide an apparatus which will remove the magnetic material, although the magnetic material may be a very small percent of the body of the material fed the separator, that is to say, which will efficiently operate upon a mixture of a very small percent of magnetic material and a very large percent of non-magnetic material without an appreciable loss of the non-magnetic material.

Embodiments of the invention are shown in the accompanying drawings, in which:

Figure 1 is a side elevation, partly in section, of one form of magnetic separator.

Figure 2 is an end view of the structure shown in Figure 1.

Figure 3 is an enlarged fragmentary plan view of a portion of the magnetic belt or traveling screen.

Figure 4 is a fragmentary sectional view through the traveling screen or belt.

Figure 5 is a view of a modified form of separator.

Referring to Figures 1 to 4, it will be seen that the separator comprises a pair of rollers 1 and 2 upon which the endless magnetic screen or belt 3 is carried. One of the rollers, for instance the roller 1, is driven through suitable reduction mechanism, such as indicated generally at 4, by means of an electric or other motor 5. Preferably one of the pulleys or rollers, for instance the roller 2, is adjustable to take up slack in the belt.

Means are provided for rapidly agitating the upper stretch of the belt or endless screen 3, and other means are provided for less rapidly though more violently agitating the lower stretch 5 of the belt. The upper agitating means may consist of a hexagonal roller 6 bearing against the belt and rapidly driven by means of the traveling belt, thereby causing the belt to rapidly vibrate, in fact at such a rate in actual practice 10 as to produce a hum. The lower agitator consists of a rectangular roller 7 which is preferably covered by means of a rubber sheath 8. The lower roller having less faces than the upper roller, vibrates the lower stretch of the belt less frequently though more violently than 15 the upper roller.

Immediately above the upper stretch of the belt an inducing magnet is positioned. This magnet may consist of a pair of longitudinally 20 extending pole pieces 9 joined by means of a single or a plurality of cores 10, each of which carries an exciting winding 11. Thus the longitudinally extending pole pieces 9 are positioned immediately above the upper stretch of the belt 25 and consequently the belt or endless screen 3 is in a very strong magnetic field and consequently is highly magnetized. The lower stretch of the endless screen is substantially out of the magnetic field, as will be immediately appreciated 30 from reference to Figure 1 of the drawings.

A hopper 12 leads downwardly and slantingly towards the upper stretch of the belt and terminates in proximity to such belt or endless screen. The powdered material is placed in the hopper and feeds downwardly upon the traveling screen or belt and is removed by the motion of the belt below the hopper. Obviously, any suitable means of feed could be employed, although 35 from actual practice, it has been found that this type of feed is highly satisfactory. Below the upper stretch of the belt or screen a collecting hopper 13 is positioned and it is preferable though not necessary to divide this hopper into two sections, as shown in Figure 2, so that the non-magnetic material will discharge to opposite sides of the machine and a relatively steep slant for the hopper is obtained. A second hopper or lower hopper 14 is positioned below 40 the lower stretch of the belt and may have a central discharge space. This lower hopper is designed to collect the magnetic material.

The mechanism is preferably carried by means of a metal frame work, indicated generally 45 at 15, which is of open work construction and provides free access to all of the parts of the separator.

Referring to Figures 3 and 4, it will be seen that the magnetic screen or belt 3 consists of a plurality of links of soft iron wire preferably 50 formed in successive convolutions and held together in any suitable manner, as by means of the transverse pins 16. The belt or endless screen is formed, as stated, of soft iron or other 55 magnetic material, so that it is readily highly magnetized when it passes into the strong magnetic zone and is readily demagnetized when it passes from such zone.

It is to be noted in this connection that the belt has open spaces between successive meshes 60 so that the non-magnetic material may pass freely through the belt while the belt is in the intense magnetic field. The upper agitator 6 keeps the belt constantly rapidly vibrating so 65 that the non-magnetic material sifts through

the belt or endless screen and substantially all portions of the mixture of magnetic and non-magnetic material contacts at one time or another with the portions of the belt. By forming the belt relatively thick, as shown in Figure 5 70, it is possible to secure a somewhat double action, that is to say, to provide both upper and lower portions of each link or convolution, so that an additional chance of contact is afforded the magnetic material with the portions of the 10 endless screen.

The inductively magnetized screen shown and described in detail is commonly known in the trade as a woven screen. It is so flexible about lines at right angles to its length that it may 15 be wrapped about a very small cylinder with the utmost freedom. It is relatively rigid transversely primarily due to the transverse coupling rods or wires 16. These features render this belt eminently satisfactory in the novel combination disclosed. For example, it may be very freely agitated; it may be freely bent around the drums over which it travels, and yet it does not sag transversely. In addition to these features, it has the open spaces at all points and 20 presents an enormous surface area of the inductively magnetized iron wires composing the belt.

The endless screen has a substantial amount of body and consequently a large amount of 30 magnetic flux may be carried by the screen, thus insuring adherence of the magnetic material to the portions of the screen. The rapid vibration of the screen by means of the upper agitator insures the free passage of the finally 35 divided, non-magnetic material through the screen. The machine actually has a very high capacity, although securing a separation of a remarkable degree.

The endless screen passes around the pulley 40 or roller 1 out of the magnetic field and the clinging particles of magnetic material are removed from the lower stretch of this endless screen or belt by the lower agitator 7. This lower agitator gives the lower stretch of the belt 45 a relatively rapid vibration, though preferably of a lesser rate than that imparted to the upper stretch. However, the lower agitator vibrates the lower stretch of the belt considerably more violently than the upper agitator.

It is to be noted in this connection that it is a well known fact that where magnetic material 50 clings to other magnetic material, that it is necessary to give a blow or sharp impact in order to cause the separation of the clinging magnetic material. This is accomplished by the relatively more violent blows struck the lower stretch of the belt by the lower agitator. In other words, any tendency for magnetism to remain either in the adhering particles or in 55 the lower stretch of the belt is avoided by actually striking the lower stretch of the belt rapid and relatively hard blows.

It has been found that the rubber sheath 8 around the rectangular lower agitator is somewhat rounded at the corners, and also it has 60 been found that it clings better to the lower stretch of the belt. Although the lower agitator may be of rectangular shape, as shown, nevertheless it is rotated very readily by the traveling 65 belt. Apparently there is somewhat of a clinging action between the rubber sheath 8 and the lower stretch of the belt. The upper agitator being more nearly round due to its hexagonal shape, does not in reality need these rubber 70 75

sheaths, although if desired, such sheath could be added. In addition to this, it is obvious that the exact shape or the exact construction of the agitator may be varied.

5 In actual operation of this apparatus it has been found that the separator will efficiently and rapidly operate upon very fine powdered material containing as low as .25 of 1% of magnetic material, and will reduce this magnetic content to as low as .005 of 1% of magnetic material. This remarkably low reduction in magnetic content is obtained without an appreciable loss of the non-magnetic material.

10 The invention may take other forms, one of which is illustrated in Figure 5.

15 In this form of the invention the same principle is employed, namely, the non-magnetic material is removed from the magnetic material while the magnetic material is in an intense 20 magnetic zone. In this form of the invention the endless screen is indicated by the reference character 17 and is carried by an upper roller 18 and a pair of lower rollers 19 and 20, an intermediate roller 21 being provided for the 25 lower stretch of the belt. The roller 19 is carried within a lower hopper 22, which is provided with a drain pipe 23. The material is supplied from a hopper or open top tank 24, which in 30 turn is constantly replenished by means of a supply pipe 25.

35 In this form of the invention the finally divided material is fed in a stream of water or other liquid to the separator. Preferably an agitator or paddle 26 is positioned in the lower portion of the supply tank 24. The liquid flows out of the tilted supply tank 24 carrying the suspended mixture of magnetic and non-magnetic material, over on to the upwardly traveling stretch of the belt or endless screen.

40 This screen passes adjacent the longitudinally extending poles 27 of the electromagnet and is consequently highly magnetized. The upwardly traveling stretch of the belt in this magnetic zone also passes between the side plates 28 and 45 over the slanting baffles 29. In reality the flow of the liquid carrying the material is roughly as indicated by the curved arrows in Figure 5, and it will be seen that this material carrying liquid passes back and forth through the screen 50 a number of times before it is discharged into the discharge hopper 22 for the non-magnetic material and liquid.

55 It is preferable to form the shield plates 28 and the baffles 29 as well as the bottom portion 30 of the trough 30 of non-magnetic material.

60 It is also preferable in both forms of the invention to have the pulley or roller over which the belt passes in leaving the magnetic zone somewhat closely positioned with respect to the pole pieces. For example, in Figure 5 the intermediate pulley 21 is close to the upper edges of the pole pieces 27, and in Figure 1 the pulley 1 is close to the rear ends of the pole pieces 9. Thus the pulleys over which the endless screen 65 passes in leaving the magnetic zone are somewhat within the influence of the magnets with the result that the endless screen in passing over these pulleys is not yet demagnetized.

69 In the form shown in Figure 5 the pulley 20 is located in the collecting hopper 31 for the magnetic material. The magnetic material is washed off from the belt by means of the passage of the belt through the liquid, such as the water in the hopper 31, the water in the hopper 70 being maintained by means of a constant spray

75 from the spray pipe 32 and overflowing through the overflow port 33.

80 A discharge pipe 34 is provided for the lower portion of the hopper 31 and whenever it is desirable the valve controlling such pipe may 5 be opened and the relatively heavily loaded liquid carrying the magnetic material may be discharged. Similarly, a hand valve is preferably provided in the pipe 23, although normally the pipe 23 is left open.

85 It is to be noted that the spray pipe 32 with its nozzles directs streams of water slantingly downwardly upon the upwardly traveling portion of the screen or belt 17 and wash any adhering magnetic particles from such belt. The 15 major portion of the magnetic particles, however, are washed from the belt by its passage downwardly into and upwardly through the liquid in the tank or hopper 31.

90 It will be seen that a novel form of magnetic 20 separator has been provided by this invention which although producing a very desirable result and fulfilling an urgent demand, is nevertheless of relatively simple and reliable construction and may be readily produced by ordinary machine shop processes.

95 It will be seen further that the separation is accomplished and carried to a very high degree without an appreciable loss of the non-magnetic 30 product.

100 It will be seen further that a novel method of operation has been provided whereby the non-magnetic material is removed from the magnetic material, thus reversing the usual steps in the process and securing a far better 35 result.

105 Although this invention has been described in considerable detail, it is to be understood that such description is intended as illustrative rather than limiting, as the invention may be variously 40 embodied and is to be interpreted as claimed.

I claim:

1. A magnetic separator comprising an endless screen formed of magnetic material, a pair of spaced drums upon which said member is 45 carried, means for driving one of said drums, means feeding material upon one stretch of said endless screen, means for magnetizing such stretch of said screen to cause the magnetic material to cling to such stretch while the non- 50 magnetic material passes therethrough, and a polygonal roller across which the other stretch of said screen passes, whereby the rotation of said roller vibrates the last mentioned stretch of said screen to remove the magnetic material 55 therefrom.

2. A magnetic separator comprising an endless screen formed of magnetic material, a pair of spaced drums upon which said member is 60 carried, means for driving one of said drums, means feeding material upon one stretch of said endless screen, means for magnetizing such stretch of said screen to cause the magnetic material to cling to such stretch while the non- 65 magnetic material passes therethrough, a polygonal roller across which such stretch passes for vibrating said stretch to remove the non-magnetic material, and a polygonal roller across which the other stretch of said screen passes, whereby the rotation of said roller vibrates the 70 last mentioned stretch of said screen to remove the magnetic material therefrom.

3. A magnetic separator comprising an endless screen formed of magnetic material, a pair of spaced drums upon which said member is 75

carried, means for driving one of said drums, means feeding material upon one stretch of said endless screen, means for magnetizing such stretch of said screen to cause the magnetic material to cling to such stretch while the non-magnetic material passes therethrough, a polygonal roller across which such stretch passes for vibrating said stretch to remove the non-magnetic material, and a polygonal roller across which the other stretch of said screen passes, whereby the rotation of said roller vibrates the last mentioned stretch of said screen to remove the magnetic material therefrom, the first mentioned roller giving said screen a more rapid 15 vibrating motion of less amplitude than said second mentioned roller.

4. In combination, a magnetic separator comprising a primary and a secondary magnet, said primary magnet consisting of two poles of magnetic material in spaced relation having extended faces, a series of cores of magnetic material, a series of electrical coil windings around said cores in assembled relation, said cores being in a parallel plane and having said poles attached thereto and extending downwardly and at right angles to said cores, said primary magnet having a horizontal magnetic field, the secondary magnet comprising a horizontal flexible woven wire screen belt formed of magnetic material having mesh openings and mounted on drums for continuous travel in and out between the poles and field of said primary magnet, in the plane of said horizontal field, and parallel to the extended faces of the poles and at right 35 angles to the said poles.

5. In combination, a magnetic separator comprising a fixed primary magnet having extended poles producing a field extending in approximately a plane from pole to pole, a secondary magnet comprising a moving flexible woven screen belt of magnetic material adjacent and at right angles to the extended poles of said primary magnet and having an active portion lying within the plane of said magnetic field, means for causing said belt to travel into and out of the field of said primary magnet, said primary magnet being used only to inductively magnetize said secondary magnet in its travel in and out of said primary magnetic field.

50 6. In combination, a magnetic separator comprising a fixed primary magnet having extended poles producing a field extending in approximately a plane from pole to pole, a secondary magnet comprising a moving flexibly woven screen belt adjacent and at right angles to the extended poles of said primary magnet and having an active portion lying within the plane of said magnetic field, said secondary magnet being inductively magnetized by short circuiting 55 the magnetic lines of force between the poles of said primary magnet.

65 7. A magnetic separator comprising a primary magnet member, a flexible screen formed of relatively movable elements of magnetizable material forming a secondary induced magnetic member, said screen being mounted between the poles of said primary magnet at right angles thereto and with its opposite longitudinal edges adjacent thereto and with its central portion 70 remote from the poles, and forming a natural return path for the magnetic circuit transversely across said screen.

75 8. A magnetic separator comprising a primary magnet and a secondary, induced magnet, comprising a flexible screen formed of articu-

lated elements of magnetizable material, means for continuously moving said secondary magnet in a parallel plane, in and out of said primary magnetic field with its opposite longitudinal edges adjacent the poles of said primary magnet and with its intermediate portion remote from said poles, whereby said screen is sectionally magnetized by induction.

9. A magnetic separator comprising a primary magnet and a secondary, induced magnet 10 formed of articulated elements of magnetizable material forming a screen, means for moving said inductively magnetizable screen through the primary magnetic field and at right angles to the poles of said primary magnet with its 15 opposite longitudinal edges adjacent the poles of said primary magnet, at a predetermined speed, means for discharging a mixture of magnetic and non-magnetic material thereon, and means for agitating said screen, whereby the 20 magnetic material will cling to said screen and the non-magnetic material will pass through said screen within the magnetic field.

10. A magnetic separator comprising an endless flexible screen formed of relatively movable 25 members of magnetic material, means for producing a magnetic field, means for passing said screen into and out of said magnetic field with the magnetic lines of force extending transversely across and in the plane of said screen 30 at right angles to the line of travel of said screen, means within the magnetic field for supplying said screen with a mixture of magnetic and non-magnetic material while said screen is within said magnetic field, whereby the non- 35 magnetic material passes through said screen while within said magnetic field and the magnetic material clings to said screen, and means for removing the magnetic material from said screen when said screen is out of said magnetic field. 40

45 11. A magnetic separator comprising a flexible traveling member formed of intermeshing relatively movable members of magnetic material, means for producing a magnetic field into and out of which said member passes with the magnetic lines of force extending transversely across and in the plane of said screen at right angles to the line of travel of said screen, means within the magnetic field for supplying a mixture of magnetic and non-magnetic material to 50 said member, means for removing the non-magnetic material from said member while within said magnetic field, and means for subsequently removing the magnetic material from said member outside of said magnetic field. 55

55 12. A magnetic separator comprising means for producing a magnetic field and a traveling magnetic member movable into and out of said field, means within the magnetic field for discharging a mixture of magnetic and non-magnetic material upon said member, the lines of force of said field extending transversely across and in the lane of said traveling magnetic member and at right angles to the direction of travel of said member, means for vibrating said member while said member is within said field to cause said non-magnetic material to pass through said member while the magnetic material clings to said member, and means for vibrating said member outside of said field to 70 remove the magnetic material therefrom.

60 13. A magnetic separator comprising means for producing a magnetic field and a traveling flexible magnetic member passing into and out of said field, means within the magnetic field 75

- for discharging a mixture of magnetic and non-magnetic material upon said member while said member is within said field, the lines of force of said field extending transversely across and 5 in the plane of said traveling magnetic member and at right angles to the direction of travel of said member, means for vibrating said member while said member is within said field to cause said non-magnetic material to pass 10 through said member while the magnetic material clings to said member, and means for vibrating said member outside of said field to remove the magnetic material therefrom.
14. A magnetic separator comprising an endless screen belt of magnetic material, means for producing a magnetic field, means for passing said screen into and out of said magnetic field, means for supplying a liquid having suspended magnetic and non-magnetic material therein to 15 said screen within said magnetic field and passing said liquid back and forth through said screen a plurality of times while said screen is in said magnetic field, to cause the non-magnetic material to pass from said screen and the magnetic material to adhere to said screen, and means for passing said screen through liquid washing means distinct from said first mentioned liquid for removing the magnetic material adhering to said screen, when said screen 20 is out of said magnetic field.
15. A magnetic separator comprising a screen flexibly formed of intermeshing elements of magnetic material, said screen being in the form of an endless belt, magnetic means for 25 producing a field transversely across said belt so that the elements of said belt form a path for the magnetic flux transversely of said belt from element to element and from one longitudinal edge to the other, means for moving 30 said belt to cause said belt to pass through and out of said field and means for feeding a mixture of magnetic and non-magnetic material to said belt while said belt is in said field.
16. A magnetic separator comprising a primary magnet member, a flexible endless screen belt formed of relatively movable elements of magnetizable material forming a secondary induced magnetic member, said screen being carried by spaced drums and being mounted between the poles of said primary magnet at right angles thereto and with its opposite longitudinal edges adjacent thereto and forming a natural return path for the magnetic circuit transversely across said screen, one stretch of said screen 40 only between said spaced drums being magnetized.
17. A magnetic separator comprising a primary magnet member, a screen formed of relatively movable elements of magnetizable material and forming a secondary induced magnetic member, said screen being bendable along lines transversely of said screen and being relatively rigid in a direction at right angles thereto, whereby sagging of said screen is prevented, said screen being mounted between the poles 45 of said primary magnet and at right angles thereto with its opposite longitudinal edges adjacent thereto and forming a natural return path for the magnetic circuit transversely across said screen.
18. A magnetic separator comprising an endless belt of magnetic material, means for producing a magnetic field, means for passing said screen into and out of said magnetic field,
- means for supplying a liquid having suspended magnetic and non-magnetic material therein to said screen within said magnetic field and passing said liquid back and forth through said screen a plurality of times while said screen is 5 in said magnetic field to cause the non-magnetic material to pass from said screen and the magnetic material to adhere to said screen, liquid washing means including a tank of liquid, and a spray distinct and separate from said first mentioned liquid for removing the magnetic material adhering to said screen when said screen is out of said magnetic field.
19. The method of separating finely ground magnetizable from non-magnetizable material 15 consisting in producing a main magnetic field, spreading the material out in a sheet, temporarily supporting the material while spread out in the form of a sheet, and passing the sheet of material through said main magnetic field at 20 right angles to said field with the poles of said field located adjacent the marginal edges of said sheet of material, producing intense local fields at the exact point of separation to hold the magnetizable material at the local intense fields, 25 and moving the said intense local fields at right angles to the main magnetic field, whereby the magnetizable material will be carried out of said main magnetic field, and the non-magnetizable material will drop away at an angle to 30 said main magnetic field while in said main magnetic field.
20. The method of separating finely ground magnetizable from non-magnetizable material, 35 consisting in producing a main magnetic field, spreading the material out in a sheet, temporarily supporting the material while spread out in the form of a sheet, and passing the sheet of material through said main magnetic field at right angles to said main magnetic field with 40 the poles of said field located adjacent the marginal edges of said sheet of material and forming local intense magnetic fields at the sheet of material to hold the magnetizable material at the local intense fields, and causing 45 the non-magnetic material to fall down away from the sheet of material at approximately right angles to the main magnetic field while in the main magnetic field, and removing the magnetic material from the main magnetic field 50 and collecting the magnetic material.
21. The method of separating finely ground magnetizable from non-magnetizable material comprising producing a main magnetic field, 55 spreading the material out in a sheet, temporarily supporting the material while spread out in the form of a sheet, and passing the sheet of material at right angles to said main magnetic field and through said main magnetic field, forming a multitude of local intense magnetic fields at the sheet of material with the flux due to said local intense magnetic fields extending in a multitude of different angular directions to preclude the escape of magnetic material from the material while in the main 60 magnetic field, allowing the non-magnetic material to drop down away from the plane of the sheet of material at approximately right angles thereto while in the main magnetic field, and moving the magnetic material held at the 65 local magnetic fields from said main magnetic field.

ROSWELL H. STEARNS.
